UNITED STATES PATENT OFFICE.

HARRY K. B. DAVIS, JR., OF HOLYOKE, MASSACHUSETTS, ASSIGNOR TO THE SWING-RITE CO. INC., OF PROVIDENCE, RHODE ISLAND, A CORPORATION OF RHODE ISLAND.

SECTIONAL SHAFT FOR GOLF CLUBS AND THE LIKE AND METHOD OF MAKING SAME.

Application filed July 12, 1923. Serial No. 651,134.

To all whom it may concern:

Be it known that I, HARRY K. B. DAVIS, Jr., a citizen of the United States, and resident of Holyoke, in the county of Hampden and State of Massachusetts, have invented certain new and useful Improvements in Sectional Shafts for Golf Clubs and the like and Methods of Making Same, of which the following is a specification.

10 My present invention relates to improvements in the construction of bamboo shafts designed more particularly for golf clubs and the like.

The invention aims to secure such a shaft 15 made up of sections in such a manner that provision is made for any inequalities in the sections, and in which surplus glue when assembling the sections may be forced inwardly to the center of the shaft and, therefore, will be prevented from accumulating 20 on the exterior surface of the shaft.

The invention further aims to provide a construction where the sections of the shaft fall just short of extending to the center, 25 whereby there will be a certain release of torsional stress in the action of play, and a leeway will be allowed for atmospheric changes, resulting in a shaft which will maintain its straight condition and have 30 more permanency in its glued joints.

With these various objects in view, the invention includes the novel article and method of making the same as hereinafter described, and defined by the appended 35 claims.

The invention is illustrated in the accompanying drawing, in which:

The figure is a perspective view of a sufficient portion of a club shaft to illustrate 40 the invention.

Referring by reference characters to this drawing, the club or other shaft, is shown as comprising a plurality of sections or strips 1 of wood preferably of split bamboo, which are of segmental shape in cross section and are laid side by side with the grain of the wood running lengthways of the shaft so that when a plurality of these sections are assembled they form a substantially circular rod or shaft having a central longitudinal opening or passage 1^a, which is provided by making the segments of a thickness less than the length of the transverse radius of the completed shaft. Prior

to being assembled, the side edges of the 55 segments 1^b are coated with glue, and after assembly the strips are wound throughout the length of the shaft with a cord 2 under strong tension to exert a progressive pressure along the length of the shaft, and the 60 glue is allowed to dry while so wound after which the cord is removed. If there are any inequalities in the several strips or sections the central opening 1^a will allow for automatic adjustment, or in other words, 65 allows for any individual strip to be forced down by the wrapping in contact with its neighboring strip or strips to insure perfect contact of the contiguous glue-coated surfaces, and in position so that the outside 70 of the handle will be truly cylindrical. The central opening permits a radial adjustment of the sections to insure perfect contact of the adjacent surfaces whether or not a soft core should be positioned in this center. 75 This opening also allows for the reception of any surplus glue which may be forced into the channel to permit of perfect seating instead of trapping this surplus or any bunches which may be contained therein and 80 so preventing a perfect seating. Then again, by receiving the surplus glue this openings also prevents this surplus from being squeezed out of the periphery and thereby causing the wrapping to adhere to 85 the outer surface of the rod or shaft to interfere with its ready removal.

I have also found that by providing the shaft with a hollow center, there is a release 90 of the torsional stress in the action of play, and also there is a leeway allowed the bamboo in atmospheric changes, that increases 95 the permanency of the glued joints and holds the shaft straight.

By the term "hollow sectional bamboo 95 shaft" I mean a shaft in which the sections of bamboo are of a thickness slightly less than the transverse radius of the completed shaft even though the hollow portion 100 may contain a filling of glue or a material softer than that of the bamboo sections.

The foregoing description is directed solely towards the construction illustrated, but I desire it to be understood that I reserve the privilege of resorting to all the 105 mechanical changes to which the device is susceptible, the invention being defined and

limited only by the terms of the appended claims.

Having thus described my invention, what I claim is:—

- 6 A hollow shaft for golf clubs comprising a plurality of assembled sections of split bamboo glued together, each section having the grain of the wood running longitudinally thereof and being of segmental form in 10 cross section, the thickness of said segments being slightly less than the length of the transverse radius of the completed shaft,

the said sections when assembled forming a central longitudinal bore providing space 15 into which the inner edges of said sections may be forced during assembling, whereby the sides of each section are firmly seated in engagement with the sides of contiguous sections, said bore being provided with an unfilled space of sufficient volume to also 20 receive excess glue.

In testimony whereof, I affix my signature.

HARRY K. B. DAVIS, JR.
